FLUME OUTLET

Edward Milo Norum, Jr., Honolulu, Territory of Hawaii, assignor to Hawaiian Development Company, Ltd., Honolulu, Territory of Hawaii, a corporation of the Territory of Hawaii

Application July 26, 1956, Serial No. 599,075

5 Claims. (Cl. 61—14)

The present invention relates to an improved flume outlet particularly useful in the irrigation of furrow crops where it is desired to control the flow of water from an irrigation flume into a furrow.

The flume outlet described herein is generally a body of elastic material with means incorporated therein for quickly attaching and detaching the same from a flume which is provided with a generally rectangular aperture. The flume outlet incorporates a simple valve structure in the form of a slidable plate for controlling the flow of water from the flume.

A general object of the present invention is to provide an improved flume outlet for irrigation flumes.

A specific object of the present invention is to provide an outlet device which is readily affixable to a flume and to provide a positive seal therewith.

Another specific object of the present invention is to provide an improved flume outlet which may be easily and quickly attached to and removed from the flume.

Another specific object of the present invention is to provide a flume outlet that minimizes turbulence and provides minimum energy loss.

Another specific object of the present invention is to provide an improved flume outlet which minimizes the accumulation of foreign material that otherwise would tend to reduce the discharge rate.

Another specific object of the present invention is to provide an improved outlet device which, when removed from the flume, leaves no protuberances in the flume.

Another specific object of the present invention is to provide a flume outlet having a throat cross-section that attracts flow and offers a minimum amount of resistance to flow.

Another specific object of the present invention is to provide a flume outlet having a discharge section which delivers water to the furrow with a minimum amount of soil erosion.

Another specific object of the present invention is to provide an improved flume outlet having a discharge section which offers a minimum of resistance to the flow.

Another specific object of the present invention is to provide a flume outlet having a discharge or outlet section which offers a minimum energy loss.

Another specific object of the present invention is to provide an improved flume outlet having a valve or flow regulating element with the valve seal being provided in a simple and expeditious manner.

Another specific object of the present invention is to provide a flume outlet of this type which has a discharge adequate to cover all situations as dictated by conditions in the furrow.

Another object of the present invention is to provide an improved flume outlet having all of the features mentioned above in a simple and relatively inexpensive device.

The features of the present invention which are believed to be novel are set forth with particularity in the appended claims. This invention itself, both as to its organization and manner of operation, together with

2

further objects and advantages thereof, may be best understood by reference to the following description taken in connection with the accompanying drawings, in which:

5 Figure 1 is a view in side elevation of a flume outlet embodying features of the present invention attached to a flume, the upstream side of the flume being to the right and the downstream side of the flume being to the left.

10 Figure 2 is a view taken in the direction indicated by the arrows 2—2 in Figure 1.

Figure 3 is a sectional view taken substantially on the line 3—3 of Figure 2.

Figures 4 and 5 are sectional views taken substantially on corresponding lines 4—4 and 5—5 in Figure 3.

15 Figure 6 shows, in enlarged form, a portion of the structure illustrated in Figure 3.

Figure 7 is a top plan view of the flume outlet.

The flume outlet, having the general reference numeral 10, is of elastic or resilient material, with the exception 20 of the slidable valve plate 11, and is adapted to be quickly attached to and removed from the water carrying flume 12. For this purpose, the flume 12 is provided with a generally rectangular apertured portion 12A, so that no protuberances extend into or below the flume when the 25 flume outlet 10 is removed.

The flume outlet comprises generally an inlet section 15, a throat section 16 and a discharge or outlet section 17, the valve plate 11 being in a position to effectively divide the throat section 16 from the outlet section 17.

30 It is noted that each one of these three sections 15, 16 and 17 comprises conduits that are substantially rectangular in cross-section, with, however, rounded internal corners so as to impede to a minimum water flow. It is noted that the entrance to the inlet section 15 is defined generally by the peripheral rectangular edge 19 of special construction. This peripheral edge portion 19 has formed therein a self-retaining sealing groove 20 around the outside thereof, such groove 20 being defined by a relatively small lower lip 21 and a relatively large overhanging lip 22.

35 It is noted that the overhanging lip 22 has an upstream portion 22A (Figure 3) of smaller cross-section at the upstream side than along the remaining portion of the upper lip (Figures 3 and 5), and such lip 22 is rounded around the periphery thereof to assure a streamlined fluid flow. Such peripheral edge 20 has at the downstream end of the flume outlet (Figure 3) a streamlined cantilever portion 24 which overhangs a portion of the throat section for minimizing the possibility of catching foreign material that otherwise might impede the water flow, and also to part the fluid flow in a smooth manner, thereby reducing turbulence and splashing.

40 It is observed that the throat section 16 is contiguous with the inlet section 15 and is defined by a substantially flat down-draw wall 26 which is contiguous with and extends generally downwardly from the upstream portion of the lip 20. This throat section 16 is provided with a generally rectangular open-ended groove 28 formed inwardly thereof near the lower end of the down-draw wall 26. The movable closure plate 11 is slidably mounted in the open-ended groove 28, and such open-ended groove 28 is defined by a bulbous portion 28A (Figure 6) which is arranged to resiliently contact the plate to provide a seal and to frictionally hold the plate in adjusted position in the groove.

45 The outlet section 17 is contiguous with the throat section 16 and extends below the open-ended groove 28. The outlet section 17 is in the form of an elbow having a generally rectangular conduit with rounded internal corners, the lower end of the elbow terminating in a plane inclined generally upwardly in the direction of the upstream side.

It is apparent from the foregoing description that the foregoing objects are accomplished by the structure described.

It is noted particularly that the flume outlet may be easily and quickly attached and detached from the flume by distorting slightly the elastic flume outlet. To facilitate such operations, it is noted particularly that the overhanging lip 22 provides a convenient stop when the flume outlet is manipulated into place from the position interior of the flume 12. Once inserted, there is sufficient pressure between the groove portion and the edge of the flume 12 whereby the flume outlet is self-retained and an adequate water seal is provided between the flume outlet and the flume.

It is noted also that the protuberance 24, while serving as a flow deflector designed to cut the flow smoothly, is sufficiently small to minimize the possibility of foreign material accumulation.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. A flume outlet comprising a body of elastic material having an inlet section, a throat section, and an outlet section, said inlet section being generally rectangular in cross section and having a peripheral edge portion, said peripheral edge portion having a self-retaining sealing groove around the outside thereof, said groove being defined by a relatively small lower lip and a relatively large overhanging lip, said overhanging lip having an upstream portion of smaller cross section at the upstream side than along the remaining portion of the lip and being rounded around the periphery thereof to assure a streamlined fluid flow, said peripheral edge having, at the downstream end of the flume outlet, a streamlined cantilever portion overhanging a portion of the throat section, said throat section being contiguous with said inlet section and being defined by a substantially flat down-draw wall that is contiguous with and extends generally downwardly from said upstream portion of said lip, said throat section having a generally rectangular open-ended groove formed inwardly thereof near the lower end of said down-draw wall, a movable closure plate in said open-ended groove, said open-ended groove being defined by a bulbous portion arranged to resiliently contact said plate along a portion of its peripheral edge and frictionally hold the same in adjusted position in said groove, said outlet section being contiguous with said throat section and extending below said open-ended groove, said outlet section being in the form of an elbow having a generally rectangular conduit with rounded internal corners, the lower end of the elbow terminating in a plane inclined generally upwardly in the direction of the upstream side.

2. A flume outlet comprising a body of elastic material having an inlet section, a throat section, and an outlet section, said inlet section being generally rectangular in cross section and having a peripheral edge portion, said peripheral edge portion having a self-retaining sealing groove around the outside thereof, said groove being defined by a relatively small lower lip and a relatively large overhanging lip, said overhanging lip having an upstream portion of smaller cross section at the upstream side than at the remaining portion of the lip and being rounded around the periphery thereof to assure a streamlined fluid flow, said throat section being contiguous with said inlet section and being defined by a substantially flat down-draw wall that is contiguous with and extends gen-

erally downwardly from said upstream portion of said lip, said throat section having a generally rectangular open-ended groove formed inwardly thereof near the lower end of said down-draw wall, a movable closure plate in said open-ended groove, said open-ended groove being defined by a bulbous portion arranged to resiliently contact said plate along a portion of its peripheral edge and frictionally hold the same in adjusted position in said groove, said outlet section being contiguous with said throat section and extending below said open-ended groove, said outlet section being in the form of an elbow having a generally rectangular conduit with rounded internal corners.

3. A flume outlet comprising a body of elastic material having an inlet section, a throat section, and an outlet section, said inlet section having a peripheral edge portion, said peripheral edge portion having a self-retaining sealing groove around the outside thereof, said throat section being contiguous with said inlet section and being defined by a substantially flat down-draw wall that is contiguous with and extends generally downwardly from said upstream side of the flume outlet, said throat section having an open-ended groove formed inwardly thereof near the lower end of said down-draw wall, a movable closure plate in said open-ended groove, said open-ended groove being arranged to resiliently contact said plate and frictionally hold the same in adjusted position in said open-ended groove, said outlet section being contiguous with said throat section and extending below said open-ended groove.

4. A flume outlet comprising a body of elastic material having an inlet section, a throat section, and an outlet section, said inlet section having a peripheral edge portion, said peripheral edge portion having a self-retaining sealing groove around the outside thereof, said throat section being contiguous with said inlet section, said throat section having a generally rectangular open-ended groove formed inwardly thereof near the lower end thereof, a movable closure plate in said open-ended groove, said open-ended groove being arranged to resiliently contact said plate and frictionally hold the same in adjusted position in said groove, said outlet section being contiguous with said throat section and extending below said open-ended groove.

5. A flume outlet comprising a body of elastic material having an inlet section, a throat section, and an outlet section, said inlet section being generally rectangular in cross section and having a peripheral edge portion, said peripheral edge portion having a self-retaining sealing groove around the outside thereof, said throat section being contiguous with said inlet section and being defined by a substantially flat down-draw wall that is contiguous with and extends generally downwardly from said upstream portion of said flume outlet, said throat section having a generally rectangular open-ended groove formed inwardly thereof near the lower end of said down-draw wall, a movable closure plate in said open-ended groove, said open-ended groove being arranged to resiliently contact said plate and frictionally hold the same in adjusted position in said groove, said outlet section being contiguous with said throat section and extending below said open-ended groove, said outlet section being in the form of an elbow.
